Louis Blum, Pittsburgh, Pa., assignor to Blumcraft of
Pittsburgh, Pittsburgh, Pa., a firm

Filed Oct. 30, 1961, Ser. No. 67,308

Term of patents 14 years

(Cl. D13—7)

FIG. 1.

FIG. 2 -FIG. 1 is a perspective view of a handrail unit embodying my new design;

FIG. 2 is an end perspective view of a modified form thereof.

The dominant features of the design are shown in full lines.

The post and rail in FIGS. 1 and 2 have been broken away in the center thereof to indicate indeterminate length.

I claim:

The ornamental design for a handrail unit, as shown and described.
